UNITED STATES PATENT OFFICE.

FREDERIC SHIELDS KOCHENDORFER, OF RIVER FOREST, ILLINOIS, ASSIGNEE TO
WESTERN ELECTRIC COMPANY, INCORPORATED, OF NEW YORK, N. Y., A CORPORATION OF NEW YORK.

METHOD OF AND APPARATUS FOR FORMING ARTICLES.

Application filed December 20, 1924. Serial No. 757,282.

This invention relates to methods of and apparatus for forming articles, and more particularly to a method of and apparatus for producing a reinforcing insert for use 5 in a telephone transmitter mouthpiece.

The objects of the invention are to provide an improved method of and an improved apparatus for forming an article.

According to the main features of the invention, a sheet of metal is fed into a two-position metal working apparatus. A plurality of concentrically arranged rings of circular perforations are produced in the sheet while in the first position, the perforations in each ring being uniform, but gradually increasing in diameter from the inner to the outer rings. The perforated portion of the sheet is then advanced to the second position where a combined forming and blanking mechanism, in a continuous series of operations preliminarily forms or cups the portion, blanks or severs it from the sheet, shapes it into a cylindrical form, and then removes the bottom from the cylinder. 25 An article formed in this manner may be used advantageously as a reinforcing insert for a telephone transmitter mouthpiece, such as that described in my copending application, Serial No. 757,281 filed December 20, 30 1924.

The invention will be more fully understood from the accompanying drawings, in which

Fig. 1 is a front elevation of a mechanism embodying the invention and which may be used for performing the process;

Fig. 2 is a sectional view along the line 2—2 of Fig. 1, looking in the direction of the arrows, showing the preliminary step of the forming operation;

Fig. 3 shows the metal sheet after perforation thereof;

Fig. 4 shows the forming mechanism in its final advanced position;

Fig. 5 shows the forming mechanism in its normal position with a completed article in process of being ejected, and

Fig. 6 is an elevation of the finished article.

Referring now to the accompanying drawings in which like numerals are employed to designate similar members throughout the several views, the numeral 10 refers generally to the main frame of a double action

press wherein a belt 11 leading to a suitable 55 source of power (not shown) drives a pulley 12, which through its shaft 13 and suitable gearing (not shown) drives a geared fly wheel 14. A shaft 15 integral with the fly wheel 14 has keyed thereto a pair of eccentric rollers 16 which are adapted to engage 60 a pair of rollers 17 which are mounted on an outer slide member 18 and which outer slide is adapted to be forced downwardly by the action of the rollers 16. Suitable guiding members 19 are provided for the outer slide member 18 and suitable means (not shown) are provided for raising it after it has been projected downwardly by the action of the eccentric rollers 16. An inner 65 slide member 20 is maintained in engagement with an eccentric portion of the shaft 15 by eccentric straps 21. Suitably placed on the frame 10 is a bolster 22 carrying a die bed 23.

The outer slide member 18 carries a pair of punch members 25 and 26 whose purpose will be more fully explained hereinafter, and the inner slide actuates an inner punch member 27. The punch member 27 is 80 adapted to extend farther downward than the punch member 26 as shown more clearly in Figs. 4 and 5 and as will be explained more fully hereinafter. This inner punch member is equipped with a centering pin 85 28 and a plurality of knock-off pins 29 which may be actuated by springs 30. The die bed 23 supports a perforating die 35 and a combined blanking and forming die 36. The blanking and forming die 90 comprises a ring member generally designated as 37 having forming shoulders 38 and a cutting edge 39. Another ring member 40 is adapted to be carried downwardly against springs 41 until it rests on the shoulder 50 95 of the die.

It is thought that a description of the apparatus and its operation will show in detail the manner in which the improved process is practiced. The first step in the 100 operation is a perforating of the metal sheet 45 in the perforating die, comprising the punch member 25 and the lower die member 35. After this operation the metal sheet presents the appearance shown in Fig. 3. 105 This part of the sheet 45 is then placed in the forming die 36 and centered therein by means of the pin 39. The slide member 18

in descending, due to the action of the rollers 16 and 17, causes the metal 45 to be engaged between the member 26 and the shoulders of the ring member 37, and the perforated portion of the sheet is thereby preliminarily formed or cupped as shown in Fig. 2. As soon as this forming step is completed the portion of metal is sheared from the sheet on the dotted line in Fig. 3 by the cooperation of the shearing edge of member 26 and the shoulders 39 of the ring member 37. The outermost series of perforations are thus partly cut away and the subsequent forming operation is expedited. Thereafter the eccentric portion of the shaft 15 causes the descent of the inner slide 20 carrying the inner punch member 27 to complete the formation of the article as represented in Fig. 4. When the ring member 40 engages the shoulder 50, as represented in Fig. 4, the bottom portion of the formed metal is severed therefrom as shown in this view. When the member 27 returns to its normal or uppermost position the springs 41 expand, actuating the ring member 40 to cause the shaped metal article to be ejected as represented in Fig. 5, the severed bottom portion being allowed to drop by gravity through the aperture between the springs 41. In case the severed bottom portion should not be released immediately from the punch member 27 as soon as such member starts to travel upwardly, the expansion of the springs 30 causes the pins 29 to force such portion free from the member. It will be noted that the inner and outer slides and their associated punch members 27, 26 and 25 return simultaneously to their normal positions.

The preliminary cupping operation starts a flow of the metal toward the portion containing the perforations shown in Fig. 3. The result is that the subsequent forming operation will not cause a drawing of the metal, but the metal will continue to flow after it has been severed from the main sheet in the same direction that it was caused to take by the preliminary cupping. The metal is therefore of substantially the same thickness after the forming operation is completed as it is originally.

What is claimed is:

1. The method of forming an article from

a sheet of material, which consists in producing concentric circles of graduated perforations in the sheet in which the outer perforations are larger than the inner perforations, preliminarily forming the perforated portion, severing the formed portion from the sheet, and further forming the severed portion into an article by contracting the area of the material in proportion to its distance from a central point.

2. In an apparatus for forming an article from a sheet of material, means for producing concentric circles of perforations in a portion of a sheet, means for preliminarily forming the portion, means associated with said forming means for severing the portion, means forming confining walls constituting a funnel shaped enclosure, and means for drawing the portion into the funnel shaped enclosure to give the portion its final form.

3. The method of forming an article from a sheet of material, which consists in forming groups of perforations in a sheet of material and contracting the area of the sheet by partially closing the perforations of certain of said groups.

4. The method of forming a tubular reinforcing insert from a sheet of metal, which consists in producing concentric circles of graduated perforations in the sheet, the outer perforations being larger than the inner perforations, preliminarily forming the perforated portion, severing the formed portion from the sheet, and further forming the severed portion by distorting the material along the lines of the concentric perforations.

5. The method of forming a tubular member from a sheet of metal, which consists in producing concentric circles of perforations in the sheet, preliminarily forming the perforated portion, severing the formed portion from the sheet along the outer circle of perforations, and further forming the severed portion by contracting the material along the outer circles of perforations and bending it adjacent the inner circle of perforations.

In witness whereof, I hereunto subscribe my name this 11th day of December, A. D., 1924.

FREDERIC SHIELDS KOCHENDORFER.
